US00D916957S

(12) **United States Design Patent** (10) Patent No.: **US D916,957 S**
Barlier et al. (45) Date of Patent: **** Apr. 20, 2021**

(54) **TYPE FONT**

- (71) Applicant: **Apple Inc.**, Cupertino, CA (US)
- (72) Inventors: **Guillaume P. Barlier**, San Mateo, CA (US); **Alan C. Dye**, San Francisco, CA (US); **Lisa K. Forssell**, Palo Alto, CA (US); **Joseph D. Gardner**, San Francisco, CA (US); **Aurelio Guzmán**, San Jose, CA (US); **Jason D. Rickwald**, Santa Cruz, CA (US); **Christopher J. Romney**, San Francisco, CA (US); **Nicolas V. Scapell**, Sunnyvale, CA (US); **Christopher I. Wilson**, San Francisco, CA (US)
- (73) Assignee: **Apple Inc.**, Cupertino, CA (US)
- (**) Term: **15 Years**
- (21) Appl. No.: **29/755,077**
- (22) Filed: **Oct. 16, 2020**

Related U.S. Application Data

- (63) Continuation of application No. 29/679,108, filed on Feb. 1, 2019, now Pat. No. Des. 900,925.
- (51) **LOC (13) Cl.** **18-03**
- (52) **U.S. Cl.**
